CARD STRIPPING DEVICE

Flem G. James, Pineville, N.C.

Application December 17, 1953, Serial No. 398,680

2 Claims. (Cl. 19—109)

This invention relates to an improved vacuum-operated card stripper.

In the art of stripping matted fibers from card clothing, it has been recognized that one simple and economical card stripper includes a vacuum nozzle and means for traversing it axially along the face of a rotating card cylinder to be stripped and in most instances a single vacuum means has been connected with two simultaneously-traversed nozzles, one for the main cylinder and one for the doffer cylinder. A disadvantage of these prior art constructions has been their failure to pick up dirty stripping knocked off the doffer cylinder by the doffer comb.

In prior art devices, both the doffer cylinder nozzle and the main cylinder nozzle usually have been positioned at the top of the card. Thus with prior art vacuum stripping, the vacuum nozzle for the main cylinder loosens and brings to the surface a substantial amount of very dirty fibrous waste material which it does not completely dislodge on first contact. The doffer roll removes this waste as it would remove carded fibers in normal operation and the doffer comb, in turn, removes the same dirty material before it reaches the doffer cylinder stripping nozzle with the result that this dirty waste material drops to the floor rather than being taken to a waste house along with the rest of the vacuum stripings.

In machines of this type, before the stripping operation begins, tailings of cotton come through the machine after the input of cotton is cut off. The doffer comb breaks such tailings off the doffer cylinder and these clean white tailings drop to the floor. Further, it is sometimes the practice when starting the carding operation after the card stripping operation to permit the clean white cotton to come through for two or three minutes until it obtains the proper weight before being sent through the trumpets. This "white waste" is also permitted to drop to the floor.

Normally this "white waste" is picked up by the operator and put back into the process where it again goes into the carding machine. Unfortunately, the waste cotton having fallen to the floor picks up the dirty waste material which has been dropped to the floor by the doffer comb. This is the dirtiest cotton of all the stripings. Its presence with the clean cotton tends to decrease the quality of the production from the machine. This has lowered the quality of the sliver produced with a resultant lower quality through all processing stages, even to the fabric.

One object of this invention is the provision of means for curing the above defects of prior art vacuum stripping devices. Another object of this invention is the provision of means for improving the quality of card sliver. Other objects of the invention will be more readily apparent from the detailed description of the invention and the attached drawings.

In general, the objects of this invention are accomplished by modification of prior art vacuum strippers

of the type described to provide a suction nozzle which traverses the face of the doffer cylinder along the line where it is engaged by the doffer comb.

It has been found that such suction nozzle will remove the dirty waste which would otherwise go back into the fibrous material being processed.

In a preferred card stripper construction, a single source of vacuum is connected with a first suction nozzle adapted to traverse axially along the face of the upper portion of the main card cylinder, a second suction nozzle adapted to traverse axially along the face of the upper portion of the doffer cylinder, and a third auxiliary suction nozzle adapted to traverse axially along the face of the doffer cylinder at about the line of engagement between the doffer cylinder and the doffer comb. In that construction, a single means is provided for simultaneously traversing all three nozzles.

The stripping nozzles may be traversed manually along a supporting rod or mechanically, as by a driven screw mounted in or adjacent the supporting rod. In either event, all nozzles should be moved together or in synchronism, as the primary purpose of the third nozzle is to pick up material loosened on the surface of the main cylinder and transferred to the doffer cylinder.

In practice, a satisfactory auxiliary nozzle is the open end termination of a relatively rigid tube extending from where a vacuum-source tube is mounted on a supporting rod downwardly to a position adjacent the doffer comb and the face of the doffer roll. The tube must be relatively rigid to assure that it may be maintained in a position of rather close and uniform clearance with respect to the doffer roll and the doffer comb.

It is important that the cross sectional dimensions of the conduits connecting the vacuum source and the three nozzles be so regulated that the proper amount of suction is applied at each point. There must be a more careful proportioning of velocity of air from the auxiliary nozzle than at either of the other nozzles, because the waste material knocked off the doffer cylinder by the doffer comb must pass around the doffer comb before it enters the auxiliary nozzle. The comb supports make it impossible to lower the traversing nozzle to the level of the bottom of the comb. Manual means for regulating the air flow can be added, if desired, in the form of valves, but inasmuch as a constant ratio of air flow will be used throughout the life of the stripper, it has been found preferable to regulate the air flow by regulating the size of the conduits leading to the respective nozzles. The type of conduit and the connections between the conduits form no part of this invention and can be varied by those skilled in the art.

While this invention is described primarily with respect to a system in which there are two primary nozzles, one for each cylinder and an auxiliary nozzle adapted to be positioned adjacent the doffer comb, it will be understood that it is within the scope of this invention to provide a stripping assembly utilizing only two nozzles, one of which is the ordinary stripping nozzle for the main cylinder and the other combines the functions of the main doffer cylinder nozzle and the auxiliary nozzle. In this alternative construction, the doffer cylinder nozzle has a close clearance from the face of the doffer cylinder above the doffer comb as well as a close clearance above and behind the doffer comb.

The invention will be better understood by reference to the attached drawings in which:

Fig. 1 is a perspective view of a portion of a card equipped with the stripping assembly of the present invention.

Fig. 2 is a diagrammatic cross sectional view showing the form of the invention shown in Fig. 1.

Fig. 3 is a diagrammatic cross sectional view of an

alternative modification of the invention which utilizes only two nozzles.

Figs. 4, 5, 6, and 7 illustrate alternative types of nozzles which may be used to regulate the relative air flow between the various nozzles shown in the other figures.

In that form of the invention shown in Figs. 1 and 2, a card stripping assembly indicated generally at 10 is mounted for reciprocation on a rod 12, which is supported on a card by means not shown, so that it is parallel to the axis of the cylinders and just above the doffer cylinder. The stripping assembly is made up of a collar 14, a main vacuum conduit 16 and three secondary vacuum conduits 18, 19 and 20, provided with nozzles 28, 29, and 30, respectively. The only parts of the card illustrated are the conventional main cylinder 40, the doffer cylinder 42 and the doffer comb 44, all of which are supported and operated by conventional means not shown. The stripping assembly is made up of metallic parts having sufficient rigidity to prevent them from moving out of predetermined clearance.

In operation, the stripping assembly remains idle at one side of the card during the normal card operation. After several hours use, the card must be stopped, cleaned of operating fibrous material and stripped to remove dirt and waste which accumulated in the card clothing. In stripping, the stripping assembly is moved to a position at the left of Fig. 1, vacuum is applied through primary conduit 16 and secondary conduits 18, 19 and 20. The card cylinders are rotated and the stripping assembly is moved from left to right so that each of the nozzles travels across the face of a cylinder. Easily removable waste is removed from the face of cylinders 40 and 42 by vacuum applied at nozzles 28 and 29 respectively. Some of the waste on the card clothing of the main cylinder is not completely dislodged by the first vacuum application. Such waste is removed by the doffer cylinder in the usual manner. That waste is dislodged by vibration of the comb and is caught up by the suction from nozzle 30 which creates an upward movement of air below the level of the comb and carried to a waste house, not shown, via ducts 20 and 16.

In the modification illustrated in Fig. 3, a stripping assembly 110 includes nozzles 128, 130 and appropriate communication conduits 118 and 120 respectively. In operation, the face of doffer cylinder 142 is cleaned by vacuum nozzle 130 and at the same time waste material dislodged by comb 144 is also picked up by nozzle 130.

Proper regulation of the relative air flow between the several nozzles can be accomplished by any of several means. The simplest is by proper choice of the inside diameter of the nozzles. Such nozzles are simply conduit extensions as shown at 60a and 60b in Figures 4 and 5. In a standard card stripping system modified in accordance with this invention as illustrated, the nozzle indicated at 30 has an inside diameter of about $\frac{7}{16}$ inch. This will be varied to no more than $\frac{3}{8}$ inch or $\frac{1}{2}$ inch except in cases of extremely light or heavy carding or a radical change of vacuum. In such a system, the effective inside diameter of nozzles 29 and 30 are about $\frac{5}{16}$ inch and $\frac{1}{2}$ inch, respectively.

As an alternative, optional dampers 50, 54, 52, 150, and 152 are shown in conduits 18, 19, 20, 118 and 120, respectively, for manually regulating flow through the several nozzles and conduits. Likewise, the eccentric-passage adjustable nozzles illustrated in Figures 6 and 7 may be substituted at 28, 29, 30, 128, and 130 or just at 30 and 130 to give extremely accurate flow control.

In Fig. 6, a substitute conduit 60c has a threaded terminal enlargement 66 provided with an off-center passage 65.

A shouldered nozzle terminal provided with a passage

64 extending from its center at its terminus to an off-center position at its shouldered end, is rotatably attached to the terminal 66 by a shouldered apertured and threaded cap 62. A friction disc 63 is fixed at the shouldered end of nozzle terminal 61 to hold the off-center passages 64 and 65 in any desired degree of alignment—thereby controlling the rate of flow through the nozzle and the conduit.

10 In Figure 7, a similar construction includes off-center passages 74 and 75, a threaded conduit terminal enlargement 76 and an interiorly threaded nozzle 71 which is secured in the desired position of adjustment by jam nut 73.

15 Thus it will be seen that by use of the device constructed in accordance with the present invention, card sliver of a uniformly high quality can be obtained, because the dirtiest waste removed in the stripping operation is carried directly to the waste house by vacuum, whereas heretofore it has been deposited in the card room 20 and returned through processing.

I claim:

25 1. In combination with a carding machine having a main card cylinder, a doffer cylinder engaging said card cylinder, and a doffer comb engaging said doffer cylinder, a card stripper comprising suction nozzles connected to traverse said main card cylinder and said doffer cylinder, a vacuum source connected to said suction nozzles, a third suction nozzle positioned adjacent the point of engagement of the doffer comb and the doffer cylinder just above the upper level of the comb reciprocating area, means connecting said third nozzle to said vacuum source, and means for traversing said nozzle along with the rest of the stripping apparatus axially along said cylinders, whereby waste loosened by the vacuum operating on the main cylinder and removed by the doffer cylinder will be removed from the doffer cylinder below the doffer comb, said vacuum source being strong enough to produce, at said last named nozzle, a zone of rapidly moving air which extends to the point of engagement of the doffer comb with the doffer cylinder, and said last named nozzle being positioned with a predetermined clearance from said doffer cylinder sufficient to permit said nozzle to suck in free falling dirt particles and the like dislodged from said doffer cylinder by said doffer comb.

45 2. In combination with a carding machine having a main card cylinder, a doffer cylinder engaging said card cylinder, and a doffer comb engaging said doffer cylinder, a card stripper comprising a first suction nozzle adapted to be positioned adjacent the face of an upper portion 50 of a main card cylinder, a suction nozzle spaced adjacent said doffer comb a distance not in excess of that necessary to pick up dirty stripings and the like knocked off the doffer cylinder by the doffer comb, a vacuum source, conduit means interconnecting said nozzles and said vacuum source, means for supporting said conduits and nozzles, and means for traversing said nozzles together axially along said cylinders, whereby waste loosened by the vacuum applied to said card cylinder will be transferred to the doffer cylinder and subsequently removed 55 by the cooperating action of said doffer comb and second suction nozzle.
